Dayton & Poole

UNITED STATES PATENT OFFICE.

JOHN GRANT, OF CHICAGO, ILLINOIS.

SHIFTING ECCENTRIC.

SPECIFICATION forming part of Letters Patent No. 363,629, dated May 24, 1887.

Application filed October 26, 1886. Serial No. 217,223. (No model.)

To all whom it may concern:

Be it known that I, JOHN GRANT, of Chicago, in the county of Cook and State of Illinois, have invented certain new and useful Improvements in Shifting Eccentrics; and I do hereby declare that the following is a full, clear, and exact description thereof, reference being had to the accompanying drawings, and to the letters of reference marked thereon, which form a part of this specification.

This invention relates to that class of shifting eccentrics for steam-engines in which the eccentric engaged with the eccentric-rod is mounted upon a second eccentric fixed to the engine-shaft, so that by turning the outer eccentric upon the inner one the throw of the valve may be changed or the engine reversed. The invention relates more particularly to an improved actuating device for moving or turning the outer eccentric with relation to the inner one in a device of the character above mentioned, as will hereinafter fully appear.

The invention consists in the matters hereinafter described, and pointed out in the appended claims.

In the accompanying drawings, illustrating my invention, Figure 1 is a sectional elevation taken upon line xx of Fig. 2, showing in side or face view the two eccentrics in a device embodying my invention. Fig. 2 is a section taken longitudinally through the shaft-axis upon line xx of Fig. 1. Fig. 3 is a side elevation of the main or outer eccentric detached from other parts of the device. Fig. 4 is a similar view of the inner eccentric, or the one attached to the shaft. Fig. 5 is a detail view of a plate shown in Fig. 2 as attached to the inner eccentric, for holding the latter in engagement with the main or outer eccentric. Fig. 6 is a sectional view taken upon line yy of Fig. 2, illustrating the shifting device therein shown. Fig. 7 is a detail sectional view illustrating another form of shifting device.

As illustrated in the said drawings, A is the engine-shaft; B, the small or inner eccentric, attached to said shaft; C, the outer eccentric, mounted to rotate upon the inner eccentric, B; and D, the eccentric-rod, provided with the usual straps, D'D', engaging the peripheral surface of the outer eccentric, C. The said eccentric C is provided near its outer edge, at

one side, with a curved slot or opening, e, in the outer surface of which is formed a curved rack, C', arranged upon a circular curve concentric with the inner eccentric, B.

F is a pinion mounted in suitable bearings, b b', upon the inner eccentric, B, and intermeshing with the rack C', these parts being so arranged that when the said pinion is rotated the outer eccentric will be carried or turned about the inner eccentric. Fixed to the pinion F is a spiral screw shaft or stem, F', which extends outwardly at one side of the eccentrics parallel with the main shaft. The said screw or spiral shaft F' is engaged with a nut, G, mounted on a slide, G', which slide is supported and constructed to slide longitudinally upon the main shaft A. The said spiral or screw stem is provided with a very quick thread, so that when the nut G is moved longitudinally with reference thereto the said stem and the pinion F will be rotated, and thereby cause the desired movement of the outer eccentric.

In one convenient form of the slide G' and shifting devices therefor (illustrated in Figs. 1, 2, and 6) the said slide is provided with a sleeve, g, which is splined upon the shaft A, and with a circular ring or disk, g', attached to the said sleeve and supporting the nut, the outer surface or periphery of the said ring or disk being arranged to extend around the shaft and the spiral ring F' concentrically with the shaft. The nut G is in this case made integral with the said plate or disk g'. The disk g' is provided with a peripheral rib, g'', engaged by plates h, pivotally connected with the forks H' of a shifting-lever H.

In another form of the shifting device (shown in Fig. 7) a sliding sleeve, g, is splined upon the shaft A, said sleeve being provided with an arm, g³, in the outer end of which the nut G is formed. The sleeve g is actuated in this case by means of a shifting-lever, H, having a bent U-shaped arm, H², which is pivoted at its outer end to a ring, g⁴, running in a groove, g⁵, in the sleeve g, the bent arm H² of the shifting-lever being so shaped as to allow the passage of the stem F' in all positions of the said sleeve.

In a convenient construction of the inner cam, B, and the bearings b for the pinion F, herein shown, the said eccentric is keyed to

the shaft, and is provided at one side with a flange, b^2 , extending outwardly at one side of the eccentric to form the bearing b , the said flange b^2 forming the side bearing for the eccentric C at one side of the latter. The said eccentric C is held upon the eccentric B by means of a removable plate, B', secured against the face of the eccentric B by screws b^3 or otherwise, said plate B' being constructed to over-lap the eccentric C at its edges, and being extended at one side to form the second bearing, b' , for the pinion F. The said eccentric B is preferably provided with a flange, b^4 , surrounding the shaft at its side adjacent to the plate B', and the central aperture of the said plate is made of proper size to fit around the flange b^4 , so as to hold the said flange in position without relying solely upon the attaching-screws for this purpose.

As a convenient means of constructing the stem F', the latter preferably consists of a bar rectangular in cross-section and bent or twisted in spiral form, the nut G being provided with a rectangular aperture fitting the bar, as clearly shown in Fig. 3.

In a device comprising a stem, F', made with a continuous spiral, such as shown in Fig. 2, any movement of the outer eccentric, C, in a direction to turn it about the inner eccentric will obviously tend to turn the pinion F and shaft F', and thereby tend to move the nut G, and in a device thus made, unless the stem be quite long and the pitch correspondingly quick, a locking device for holding the shifting-lever positively in place may be desirable. The device shown is more particularly intended as a reversing device, the parts being so arranged for this purpose that when the pinion F' is at the middle of the rack C' the eccentric-rod will have no movement, and when the pinion is at opposite ends of the rack the engine-shaft will be caused to turn in opposite directions. In a device thus constructed the stem F' may be desirably provided with a straight part, f' , at its middle and other straight parts, ff^2 , at its ends, as indicated in Fig. 7, so that when the nut G is placed at either of the points mentioned the said stem will be positively locked from rotation. When the stem is provided

with straight parts $ff'f^2$, as above described, any locking devices for holding the eccentric in position at the middle or at either end of its rotary movement will obviously be unnecessary; but such locking devices will usually be provided for holding the nut at intermediate points.

I have herein shown a device for shifting the outer eccentric as applied for the purpose of reversing the engine; but a device embracing the same novel features of construction herein shown and claimed may obviously be employed in connection with that class of engine-governors in which the valves are controlled by governing devices operating to shift the eccentric upon the shaft.

I claim as my invention—

1. The combination, with an engine-shaft, an eccentric fixed on the shaft, and an outer eccentric provided with a rack, of a pinion mounted upon the eccentric which is attached to the shaft, and provided with a spiral stem, and a sliding nut engaging said stem, substantially as described.

2. The combination, with an engine-shaft, an eccentric fixed upon the shaft, and an outer eccentric provided with a rack, of a pinion mounted upon the eccentric which is attached to the shaft, and provided with a spiral stem, said spiral stem being provided with one or more straight parts or sections, substantially as described.

3. The combination, with an engine-shaft, an eccentric fixed upon the shaft, and an outer eccentric provided with a rack, of a pinion mounted upon the eccentric which is attached to the shaft, and provided with a spiral stem, a nut engaging the spiral stem, a slide encircling the shaft and stem and supporting the nut, and a forked shifting-lever engaging the slide, substantially as described.

In testimony that I claim the foregoing as my invention I affix my signature in presence of two witnesses.

JOHN GRANT.
